US00D954754S

(12) **United States Design Patent** (10) **Patent No.:** **US D954,754 S**
Nommensen (45) **Date of Patent:** **** Jun. 14, 2022**

(54) **ROD COUPLER**

(71) Applicant: **COBALT EXTREME PTY LTD**, East Brisbane (AU)

(72) Inventor: **David Nommensen**, Norman Park (AU)

(73) Assignee: **COBALT EXTREME PTY LTD**, East Brisbane (AU)

(**) Term: **15 Years**

(21) Appl. No.: **29/747,775**

(22) Filed: **Aug. 25, 2020**

(30) **Foreign Application Priority Data**

Feb. 28, 2020 (AU) 202011155

(51) **LOC (13) Cl.** **15-04**

(52) **U.S. Cl.**

USPC **D15/21**

(58) **Field of Classification Search**

USPC D8/382, 396, 397, 398; D23/249, 259, D23/260, 262, 266; D15/21, 138, 139

CPC E21B 17/1078; E21B 43/126; E21B 17/1071; E21B 17/04; E21B 17/042

See application file for complete search history.

(57) **CLAIM**

The ornamental design for a rod coupler, as shown and described.

DESCRIPTION

FIG. 1 is a left, front, top perspective view of the present rod coupler;

FIG. 2 is a right, rear, bottom perspective view of the rod coupler of FIG. 1;

FIG. 3 is a front view of the rod coupler of FIG. 1;

FIG. 4 is a rear view of the rod coupler of FIG. 1;

FIG. 5 is a top view of the rod coupler of FIG. 1;

FIG. 6 is a bottom view of the rod coupler of FIG. 1;

FIG. 7 is a left side view of the rod coupler of FIG. 1; and,

FIG. 8 is a right side view of the rod coupler of FIG. 1.

The broken lines in the drawings illustrate portions of the rod coupler and form no part of the claimed design.

1 Claim, 4 Drawing Sheets
